(57) **CLAIM**

The ornamental design for a lower grille of a front bumper, as shown and described.

DESCRIPTION

FIG. 1 is a front left elevated perspective view of a lower grille of a front bumper according to the present invention. FIG. 2 is a front left perspective view of the lower grille shown in FIG. 1.

FIG. 3 is a rear right elevated perspective view thereof.

FIG. 4 is a rear right perspective view thereof.

FIG. 5 is a front view thereof.

FIG. 6 is a rear view thereof.

FIG. 7 is a left side view thereof.

FIG. 8 is a right side view thereof.

FIG. 9 is a top view thereof; and,

FIG. 10 is a bottom view thereof.

1 Claim, 10 Drawing Sheets
